UNITED STATES PATENT OFFICE

2,168,087

MILL

Robert S. Butler, Claremont, N. H., assignor to
 Sullivan Machinery Company, a corporation of
 Massachusetts

Application December 31, 1934, Serial No. 759,905

9 Claims. (Cl. 83—9)

My invention relates to material crushing and pulverizing apparatus, from one aspect relating to improved rock-crushing apparatus, from another to improved material pulverizing apparatus 5 and from a third aspect to a combination of these.

An object of my invention is to provide an improved mill for crushing various materials such as rock, coal, ore, clinkers, residue from refining processes, like coke and petroleum coke, products

10 from various industrial processes, and like materials. Another object of my invention is to provide improved means for pulverizing materials of the type just enumerated after they have been crushed to appropriate initial sizes. A third ob-

15 ject of my invention is to provide an improved apparatus for performing both a crushing and a pulverizing function, and in itself adapted to replace gyratory or like crushers. Still another object of my invention, from one of its aspects, is

20 to provide an improved material crushing apparatus in which freely traveling impact members of various sizes may each be segregated in chambers individual thereto and move in paths so constrained that superpositioning of bodies one upon

25 another is prevented. More specifically an object of my invention from the aspect last mentioned is to provide an improved crusher in which the freely moving crushing elements are confined and controlled in such manner that a far more ef-

30 ficient crushing action is accomplished than has heretofore been possible with apparatus of remotely comparable size. From another aspect, an object of my invention is to provide a pulverizing apparatus, in which the pulverizing medium

35 is provided with a relatively long path, restricted however in a direction at right angles to its general direction of movement so that the material to be reduced can not escape the action of the pulverizing medium. From a further aspect, an

40 object of my invention is to provide a single, moving, material-reducing-chamber-providing member, suitably partitioned, and segregating in different portions thereof crushing media of different sizes, with automatic feed of material be-

45 ing processed from chamber to chamber, so that material of relatively large sizes may enter the compartment containing the largest crushing medium and progressively pass through other compartments until ultimately a finely pulverized product is delivered. From another aspect, it is an object of my invention to provide im-

50 proved feeding means delivering material to be crushed automatically in the most advantageous relation to the relatively moving parts between which a crushing action is to be effected. Still

another object of my invention is to provide an oscillatory type mill in which there is provision for continuous feed and discharge of the material. Still another object of my invention is to provide an improved crusher equally well adapted to the 5 wet and dry grinding and crushing of the materials for whose reduction it is adapted. Other objects and advantages of my invention will hereinafter more fully appear.

From one aspect, my invention comprises a 10 plural-chambered mill element, relatively movable crushing media associated with each chamber thereof, and means for effecting relative movement between the chambered element and associated media involving reversals of movement. Preferably, rapid oscillatory movement will be provided, and, very desirably, pivotal movement of the chambered element will be selected. Arcuate chamber form and graduated size of the 15 relatively movable crushing media are very ad- 20 vantageous. While, obviously, different pivot locations may be selected for the chambered element, a pivot location near the point of initial material ingress facilitates feed; and a top pivot improves smoothness of operation and makes 25 easier the discharge of processed material. Arcuate chamber form in conjunction with pivotal chamber movement increases size reduction by 30 attrition and conserves power. The use of large media and sharp impact for crushing, and large 35 quantities of small to fine media for pulverizing increases number of impacts more or less proportionately to increase in number of material particles. Chamber oscillation, as compared with 40 oscillation of the internal crushing media facilitates drive and simplifies mechanical construction. All these advantages are available with my invention, and all the features disclosed in the contemplation of my invention from its several aspects.

In the accompanying drawing, in which for purposes of illustration one form which my invention may assume in practice has been shown:

Fig. 1 is a central vertical section through a 45 mill constructed in accordance with the illustrative embodiment.

Fig. 2 is a vertical transverse section on a plane corresponding to the line 2—2 of Fig. 1.

Fig. 3 is a top view of the mill, with parts 50 broken away.

Referring to the drawing, it will be observed that a frame 1 comprising transverse body members 2, 2 integrally supporting suitably reinforced side members 3, 3, joined by an upper transverse

frame 4, later more fully described, constitutes the main support and body of the machine. The side members provide journals or bearings 5, 5 at their upper ends. At one end of the frame 5 members 3, 3 there is provided suitable support, as at 6, for a pair of journal blocks 7, in which there is rotatably mounted a power driven crank-shaft 8 carrying at one end thereof a heavy combined flywheel and driving pulley 9 and having 10 a crank 10, which is connected by a pitman or connecting rod 11 to drive the movable member 12 of the mill.

Supported in the bearings 5 are transverse stub shafts 13, from which there depends a casing 14 elongated in form and having its interior divided 15 into a plurality of mutually superimposed chambers, as will shortly be described. Within the casing 14 I provide a series of vertically superimposed compartments 15, 16, 17. Herein these 20 compartments are arcuate, and their curvature flattens as they lie more remote from the axes of the shafts 13; and the several chambers are of unequal lengths, the chambers more remote from the shafts 13 being the longer. The compartments 25 are shown as having lateral openings 18, 19, 20, closed by suitable plates 21a, 21b, 21c, suitably secured in position. In the form of construction illustrated there are three compartments, but it will be appreciated that the number 30 may be modified if desired. Chamber 15 is a primary crusher chamber, chamber 16 a secondary crusher chamber, and chamber 17 a pulverizer chamber. Chambers 15 and 16 are shown as provided with a curved end wall so as to provide 35 for a greater crushing effect due to the closer conformity in shape of these end walls to the shape of the crushing media which are confined to movement within the several chambers. The lowest chamber 17 also has concave end walls 40 and has its bottom formed by suitable means providing adequate rigidity and at the same time providing suitably sized openings for the passage of material reduced to the requisite amount, consisting, as illustrated, of a perforated wall 23 having openings 24 therethrough preferably of 45 slightly larger size than the free openings 26 through a liner 25. Obviously any suitable form of construction which will insure the necessary reduction in size of the material being pulverized prior to attaining entrance to the openings 50 formed in the reinforcing structure, may be employed. The pulverizing chamber receives crushed material through spaced openings 27, 27 from the secondary crushing chamber 16, and the last-named chamber receives initially crushed material, through an opening or openings 28, from the initial chamber 15. The chamber 15 has a supply or feed inlet opening 29, and each of the upper chambers is shown with an appropriate liner, as at 30. A stationary feed chute 31 supported by the transverse element 4 and extending well down into a top chamber 32 in the member 14 serves to permit access of the material to be processed, at all times into the reducing 55 chambers. The connecting rod 11 is connected to a wrist pin 33 supported on suitable brackets 34, carried by one of the chamber ends, so that rotation of the crankshaft 8 effects a suitable oscillation of the member 14. The lengths of the 60 several chambers 15, 16, 17 may be varied, both absolutely, and relatively with respect to each other, and their radial dimensions will be so fixed that the chambers 15 and 16 will be slightly deeper than their contained crushing media, 65 while chamber 17 may desirably be proportioned 70 75

to insure packing of its contained material from top to bottom in each end as member 14 swings.

The chamber 15 will be noted to contain a relatively freely movable crushing medium, herein in the form of a single relatively large and heavy 5 ball 35 of suitable material such as steel, alloy steel, or any other material of adequate weight, hardness, and resistance to fracture.

This crushing medium is herein confined as to vertical movement by the top of chamber 15 in 10 such manner that the movement of said member is substantially restricted as regards deviation from a relatively true arcuate path. It must, therefore, positively engage and crush the unbroken masses of material fed into its path. 15 Compartment 16 may be provided with one or more free crushing media of smaller size than element 35, if desired, but it is here shown as containing a single material-breaking element 36 of like size to element 35. Chamber 17, whose construction has previously been described, contains a substantial (a relatively large) number of crushing elements 37 of much smaller size, ranging from something less than an inch down to even one thirty-second of one inch in diameter. 20 While a single series of differently vertically positioned reducing compartments or chambers is shown in the rocker element 14 in the illustrative embodiment described, it will be appreciated that one or more parallel series of such chambers 30 may be provided in a single, so to speak, pendulum element, and thereby doubled, trebled, or otherwise multiplied capacity provided. Obviously also, if desired, a single frame may support a plural-crank drive shaft, and vibration be 35 markedly reduced by providing a plurality of pendulums with cranks spaced say 180° apart, or at some other suitable angle, actuating in opposite phase relation the different pendulums.

Reference has been made to the differences in 40 chamber dimension. With a plural stage grinding and pulverizing unit, ideal operating conditions for the various stages call for variations in chamber dimensions. The principles upon which crushing and pulverizing chamber dimension may 45 be laid out are more fully set forth in my applications, executed of even date herewith, for "crushers" and for "pulverizers" but they will be briefly explained herein. It will be evident that the maximum velocity of any given point in any 50 chamber wall may readily be determined graphically or by comparatively simple calculations when effective pendulum length and crank throw and R. P. M. are known. Having determined the force necessary to effect the crushing at each 55 stage and selected suitable means for the crushing media, and suitable sizes thereof, calculations will occasion little difficulty. Rebound being substantially discounted as a factor by reason of the presence of material to be crushed between these 60 moving bodies and the ends of the chambers, which largely eliminates rebound, the maximum velocity of chamber contents is easily computed. Theoretically the maximum kinetic energy may be made available by proportioning the length 65 of any individual chamber so that the end wall of that chamber toward which the moving crushing media is moving will be traveling at maximum velocity at the moment that the material between the crushing member and that wall is simultaneously engaged on its opposite sides by the wall and the crushing member. This result can be secured, approximately, by using a chamber of a length approximately equal to $1\frac{1}{2}M+1\frac{1}{2}S+B$; where 70 M =maximum size of entering material 75

bodies; B, the length along the arc extending between the central points in the opposite chamber ends, of the size-reducing medium; and S, the chamber stroke or overall travel measured along its arc of movement. With respect to the lowest chamber, the quantity B may be determined with the media packed in one chamber end. When lighter blows will suffice, chamber length may be reduced, or contained material or medium "length" increased so that the energy is applied with diminished sharp impact and more attrition and pressure crushing. In the event of reduction in the size of the crushing members in succeeding chambers the need for increased chamber length for increased radial distance from pivot axis lessens; and sharp impact may be decreasingly necessary, also, in the later stages.

The mode of operation of the construction described can now be briefly summarized. The material is fed in any suitable way and at any appropriate rate to the chute 31, and passes via 32 and 29 alternately to the opposite sides of the member 35 when the latter is at one end or the other of its path of travel. It will be appreciated that as the material which has thus entered the chamber is struck blows from opposite sides, as it were, by the head of the chamber 15 and the "free" crushing medium 35, there will result a number of substantial sized fragments, many of smaller size, and some dust. Accordingly, a part of the material broken in the first chamber may need little further crushing. The larger fragments and particles will be subjected to a further crushing action by the crushing member 36 in chamber 16. Material crushed by this member will, in the last chamber 17, be ground to a powder. In this last chamber, it will be appreciated that the entire mass of material, and balls or the like, will be flung back and forth from end to end of the chamber, and not only will the kinetic energy of the moving mass result in pulverization due to impact, but there will be a substantial grinding action due to attrition.

From the foregoing description it will be apparent that the embodiment described is very simple in mechanical construction, is adapted to crush, grind and pulverize relatively large quantities of material in a comparatively short period, will combine in one structure the functions of secondary crushing and of grinding, and is adapted to permit the obtaining of a very effective crushing effect due to the generation and the use of kinetic energy, all the energy not actually used in the crushing of rock or in the relatively small generation of heat which takes place during the grinding operation, being returned to the flywheel and there stored for reuse in actuation of the oscillating grinding chamber member.

While I have in this application specifically described one form which my invention may assume in practice, it will be understood that this form is shown for purposes of illustration only, and that the invention may be modified and embodied in various other forms without departing from its spirit or the scope of the appended claims.

65 What I claim as new and desire to secure by Letters Patent is:

1. In a mill, a chamber forming element supported for pivotal movement upon a substantially horizontal axis and providing at least two generally arcuate, elongated size-reducing chambers, each of which in the mid-swing position of said chamber-forming-element is disposed below a horizontal plane in which the pivot axis lies, and each having upper and lower curved walls and each spaced from said pivotal axis and each of

substantially uniform cross sectional area, on planes normal to its respective curvature and including the axis of pivotal movement of said element through the major portions of its length, means for introducing material to be reduced into one of said chambers, means for delivering it therefrom after size-reduction therein to the other, and means for the escape of the material from the latter chamber after size-reduction therein, the chamber last mentioned the more remote from said horizontal axis, and means for rapidly positively oscillating said chambers through an angle less than the angle of their respective arcs. 5

2. In a mill, a chamber-forming element providing a plurality of generally arcuate, elongated, size-reducing chambers arranged in serial communication with each other and supported for pivotal movement about a substantially horizontal axis, all of said chambers disposed, in the mid-swing position of said element, below a horizontal plane in which the pivot axis lies and each having upper and lower curved walls, both spaced from said pivotal axis, and each, further, of substantially uniform cross section on planes including 10 said axis, throughout the major portions of its length, and means for rapidly positively oscillating said chambers through an angle less than the angle of their respective arcs. 15

3. In a mill, a chamber-forming element having 20 a pivotal mounting and providing below its pivot a plurality of vertically-serially-arranged size-reducing chambers each generally arcuate and all arranged in a sector of less than 180° inclusion having its center in said pivot, and of progressively 25 increasing length as they are more remote from said pivot, and each of substantially uniform cross section on planes including said axis, and means for effecting rapidly repeated oscillation on said pivot. 30

4. In a mill, a chamber-forming element having 35 a pivotal mounting and providing below its pivot a plurality of vertically-serially-arranged size-reducing chambers each generally arcuate and conforming in curvature to arcs struck from a 40 center in the pivot axis and all arranged in a sector of less than 180° inclusion having its center in said pivot, and of progressively increasing length as they are more remote from said pivot and each of substantially uniform cross section on 45 planes including said axis, and means for effecting rapidly repeated oscillation on said pivot of less angular extent than the angle of arc of any of said chambers, said chambers having size-reducing media therein of progressively diminishing 50 size as the chambers lie more remotely from said pivot. 55

5. In combination, in a mill, a frame member, a member pivotally supported by said frame member and providing at one side of its pivot only a 60 series of chambers of increasing dimension transversely of said member from its pivotal axis, and size-reducing media in said chambers, the size-reducing media in the chamber more remote from 65 the pivot axis being the smaller.

6. In a mill, in combination, a plural-chambered mill element pivotable about an axis adjacent the top thereof and having arcuate chambers therein formed substantially on arcs struck from said 70 pivot and each having arcuate upper and lower walls, said chambers each of an angular extent less than a circle and severally struck on radii of different lengths, freely moving size-reducing media in the several chambers of said chambered 75

mill element, and means for oscillating said element about its pivot.

7. In combination, in a mill, a frame member, a pendulum member pivotally supported by said frame member and providing a plurality of arcuate chambers differently spaced from the pendulum pivot and serially communicating with each other in the order of their relative distances from said pivot and each containing a free-moving size-reducing medium and of a length to effect coaction between each chamber end and the chamber contents in material-size-reduction at least once in each complete cycle of pendulum oscillation and each of such dimension normal to its path of oscillation that at opposite ends of its pendulum movement filling from top to bottom occurs at one end, and means for oscillating said pendulum at a rapid rate.
8. In a mill, a chamber-forming member, means for supporting the same for pivotal movement, said chamber-forming member having an arcuate chamber therein and providing discharge means for the discharge during chamber movement of size-reduced material, a charge of free size-reducing media in said chamber, spaced feed openings into said chamber each spaced from the longitudinal center of the chamber and so disposed that one of them is between said longitudi-

nal center and each end of said chamber, and means for swinging said chamber-forming member oppositely through a restricted arc at a rate to effect alternate compacting of the chamber contents at the opposite ends of the chamber, said openings so located and the length, depth and movement of said chamber so determined that the opening remote from the end of the chamber in which the chamber contents are compacted may serve for feed ingress during such compacting of the contents.

9. In combination, in a mill, a frame member, a pendulum member pivotally supported by said frame member, and means for oscillating said pendulum member at a rapid rate, said pendulum member providing a plurality of arcuate chambers each of a dimension normal to its arc less than its mean radius and each containing a free-moving-size-reducing medium, and of a length to effect coaction between each chamber end and the chamber contents during material size-reduction at least once in each complete cycle of pendulum oscillation and each further of such dimension normal to its path of oscillation that at opposite ends of its contents movement filling from top to bottom occurs for at least half of its length.

ROBERT S. BUTLER.
